TIME-LIMIT SWITCH FOR ELECTRIC-LIGHT INSTALLATIONS

Application filed March 20, 1929, Serial No. 348,390, and in Germany March 22, 1927.

This invention relates to time-limit switches of the kind used in electric light installations for stairs, and particularly to such time-limit switches which are provided with 5 thermostats. The thermostat of such a time-limit switch, when subjected to the action of an electric heating coil, causes the contact of the heating circuit to be opened and the contact of the main circuit of the switch to be 10 closed. On the other hand, when the heat ceases to act on the thermostat, this will cause the contacts to be operated in reverse order during the following cooling period. The heating action, which causes the contacts to 15 be opened and closed as stated above, must take place very quickly, but the cooling and the opening of the main circuit caused thereby, should require considerable time, this being an object, for which the thermostat is 20 suitably designed.

The invention relates to improvements in formerly used time-limit switches of this type and an object of the invention is to procure a time-limit switch, in which the movement necessary for opening and closing the contacts in a simple and efficient way is obtained by the direct use of such variations of the 25 length of the thermostat itself, which are due to variations of the temperature. Formerly such variations of length have been designed to move the contact element by means of a system of levers, but according to this invention the mechanism for moving the contacts in accordance with the length variations 30 simply consists in the thermostat itself, one end of which for this object being provided with necessary contact pieces.

The invention consists in certain parts, improvements and combinations hereinafter described, and more specifically pointed out in the claims hereunto appended.

In the accompanying drawings, which constitute a part of this specification, an embodiment of my invention is principally set forth.

Fig. 1 shows a front view of the apparatus, the cover being removed in order to show the electrical connections. Fig. 2 shows a longitudinal section. The elongating element of the thermostat consists of a rod 1 arranged 45 as shown inside a tube 3 and surrounded by

a coil 2, insulated from both the rod and the tube. The lower end of the rod is connected to the tube by means of an insulating support 4 and nuts 5. The rod and the tube are preferably made of the same metal and the latter is provided with contacts 6, 7, each mounted on a spring 6¹. The movement of said springs outwardly from the tube is limited by means of stop hooks 7¹. At the upper part 55 of the thermostat the rod 1 by means of nuts 11 is connected to a fixed strap 9, the tube 3 being pivotally connected to said strap by means of a pin 8 as shown on the side of the centre line of the rod. To the tube 3 there is rigidly connected an arm 10, the free end of 60 which is pressed down by a spring 12, the force of the spring tending to turn the lower end of the tube to the right of Fig. 1.

In the position of the parts shown in the drawing the contact 6 is in contact with a contact member 13 arranged on the contact fixture 14. Directly above these contacts 6, 13 there is a coil 18 having an iron core 19 for arc-blow-out when opening the circuit 20. This circuit 20 is conducted through the coil 2 around rod 1, said coil being connected in series with coil 18. The contact 7 co-acts with another contact 21, fixed on a screw 22 arranged on a fixture 23. Said screw 22 against the action of a spring 22¹ may be adjusted 65 by means of the insulating knob 24. The main circuit 20-25 also comprises a condenser 15 for arc-blow-out when opening contacts 7, 21. The contact fixture 23 is connected to the main circuit 20-25, which contains the lamps 26. Both circuits 20, 20-25 are connected to the battery 27, said battery by means of pin 8 and tube 3 being in electrical connection with contacts 6, 7. When the heating circuit 20 of the thermostat is closed by means of one of the switches 28, the coil 2 receives an impulse of current, causing rod 1 to become quickly heated, owing to which the rod will become elongated instantaneously. This will cause the lower part of the thermostat to swing to the right, thereby closing contacts 7, 21 and the main circuit 20-25, containing the lamps 26. The initial part of 70 said movement of the thermostat to the right causes the circuit 20 to be opened. The heat- 75

ing also causes elongation of tube 3, but as the rod is situated inside of the whole construction, the elongating of the same will dominate, and at the same time the subsequent cooling of the rod will be retarded, thus causing the circuit of the lamps to remain closed during a certain space of time. By the cooling contraction of the rod the spring 12 is stretched out and the lower part of tube 3 is swung back to the left to such a degree, that the spring 6¹ on the right side has ceased to act, thereby causing contact 7 to leave contact 21. The lamp circuit is then opened and shortly afterwards the contacts, 6, 13 become closed and the apparatus may be ready for another operation as described above. The space of time during which contacts 7, 21 remain closed and consequently the lamps will continue to glow, may be controlled by operating the screw 22. The tube 3 acts as a screen preventing the heat rays emanating from rod 1 from escaping to the outside, a feature which will serve as a constant resistance to the cooling of the rod.

If by means of screw 22 the contact fixture is moved to the left, the action of spring 6¹ will increase, thereby also increasing the illuminating time, as the thermostat may be adjusted to swing at a constant angle when heated by the current. The plate 29, upon which the thermostat is mounted and the cover 30 are both made of an insulating material, for instance bakelite. The cover 30 is attached to the apparatus by means of a screw 16.

Various modifications may be made without departing from the spirit and scope of this invention, which is not to be limited to the particular details shown and described.

Having thus described the nature of our invention, what we claim as new, and desire to secure by Letters Patent, is—

1. In a time-limit switch, in combination, a thermostat, a metal tube surrounding said thermostat, means for connecting one end of said metal tube to one end of said thermostat, contact pieces secured to said end of said metal tube, a contact piece co-acting with one of said contact pieces for closing an electric circuit for heating said thermostat and opening the same when the thermostat is heated, another contact piece co-acting with the other of said contact pieces for closing an electric circuit for lighting a system of lamps when said heating circuit is opened, and means for pivotally connecting said metal tube to a fixed pin.

2. In a time-limit switch, in combination, a thermostat, a pivoted member disposed in parallel relation to said thermostat and having one end connected to one end of the thermostat, contact pieces secured to said end of said member, a contact piece co-acting with one of said contact pieces for closing an electric circuit for heating

said thermostat and opening the same when the thermostat is heated, and another contact piece co-acting with the other of said first contact pieces for closing an electric circuit for lighting a system of lamps when said heating circuit is opened.

3. In a time-limit switch, in combination, a thermostat, a pivoted member disposed in parallel relation to said thermostat and having one end connected to one end of the thermostat, contact members flexibly supported on said member at opposite sides thereof, a contact member adapted to cooperate with one of said contact members for closing an electric circuit through said thermostat thereby to heat the same, and a second contact member adapted to cooperate with the other flexibly supported contact member for closing a circuit through a lighting system, said last cooperating contact member being adjustable relative to its cooperating member.

In testimony whereof we have signed our names to this specification.

KARL EINAR RUPERT LÖFGREN.
ERIK ARTUR FAGERLUND.
